COUNTING MACHINE FOR COUNTING RECORD CARDS, CHECKS, COUPONS, AND THE LIKE

Nelson S. Welk, Athens, Ohio, assignor to The McBee Company, Athens, Ohio, a corporation of Ohio

Application July 26, 1939, Serial No. 286,570

8 Claims. (Cl. 271—51)

My invention has for its principal object to construct a machine which ensures an accurate total of the number of cards passing through the machine and to attain this object with a high speed and simple and easy operation.

5 My invention has for its further object to provide a counting machine which can be readily adjusted to count cards, etc. of various dimensions in length and width and thickness and to accomplish this with a minimum amount of adjustment.

10 My invention has for a further object the provision of means to mechanically stack the cards after they have been counted to facilitate their removal.

15 My invention has for a further object the provision of means for automatically locking the counter thereby preventing over-running of same and the miscounting of cards, etc.

20 My means of accomplishing the foregoing objects may be more fully comprehended by having reference to the accompanying drawings, which are hereunto annexed and are a part of this specification in which:

25 Fig. 1 is a side elevation of my machine showing its gear train and motor drive, the front of the machine being at the left-hand side;

30 Fig. 2 is a top or plan view of Fig. 1 on an enlarged scale with the rear or conveyor end left off;

35 Fig. 3 is an enlarged side elevation view of the end of the machine with the gear train and motor drive and with the rear or conveyor end left off;

40 Fig. 4 is an enlarged side elevation view of the opposite side from the gear train and motor drive, showing the conveyor drive, with parts of the machine broken away and in section for clarity;

45 Fig. 5 is an enlarged side elevation view of the rear or conveyor end of the machine parts being broken away and in section for clarity;

50 Fig. 6 is a cross sectional view of the conveyor end taken on line 6—6 of Fig. 5 and looking in the direction of the arrows;

55 Fig. 7 is a cross sectional view of the main feed and corrugated rollers, card locating plates and card adjusting blade taken on line 7—7 of Fig. 4 and looking in the direction of the arrows;

Fig. 8 is a cross sectional view of the second pair of feed rollers taken on line 8—8 of Fig. 4 and looking in the direction of the arrows;

55 Fig. 9 is a cross sectional view showing the counter and high speed third pair of feed rollers

taken on line 9—9 of Fig. 4 and looking in the direction of the arrows;

Figs. 10 and 11 are detail views of the spring press high speed roller;

5 Fig. 12 is a diagrammatic view of the operation of the machine showing the preliminary stacking of the cards on the conveyor belt, a card ready to be counted and the feed end of the cards to be counted;

Fig. 13 is a diagrammatic view of the counter 10 wheel being moved by a card to be counted; and

Fig. 14 is a diagrammatic view showing card counted and counter-locked to prevent additional counting.

Similar reference numerals refer to similar 15 parts throughout the entire specification.

As shown in the drawings in dot and dash lines, the operating mechanism is mounted entirely within a casing or container. This is done for two reasons,—one, to give rigidity to the supporting frame; second, in order to insulate the noise of the machine as much as possible. The container or casing is lined with some kind of soundproofing material. This I have found to be necessary because the machines are used in 20 offices and the noise should be minimized as much as possible. Inside the container or casing, I form a frame 1 which is carried by legs 2 and 3 which are tied by cross rods 3'. These rods support the electric motor 5 which drives the 25 mechanism. Side panels or plates 6 and 6' are secured to the right and left side of the frame 1. I mount two brackets 4 on the panels 6 and two similar brackets 4' are mounted on the panels 6'. These brackets support the rods 5 and 5' 30 which are slidably mounted therein. The rods 5 and 5' are connected at the front end by a cross rod 7 which carries an inclined adjustable card support 8 which supports the cards as clearly seen in Figs. 2 and 4. This card support is 35 provided with a sliding weight 8' which adds to the force of gravity for feeding the cards. This sliding weight 8' is arranged to bear upon the rearward margin of the cards only. It has been 40 found in practice that in this way I am able to attain more effective feeding. The card support 8, as clearly seen in Figs. 2, 4 and 12, is placed at an angle so that the cards 9 are held at an 45 angle to their face so as to produce a bevelled arrangement to facilitate their feeding. This 50 inclined card support must be made adjustable because if the inclination is too sharp or is insufficient, it will prevent proper feeding of the cards. By mounting the inclined card support 8 upon the slidable rods 5 and 5', once the proper 55

inclination is determined, it can always be maintained regardless of the size of the cards to be counted. The forward edge of the cards contact locating plates 10 and 10' which are adjustably mounted on a rod 11. These plates are provided with hubs which may be cast or formed thereon or readily attached by welding or any other convenient method of securing them to the plate. Set screws 12 and 12' are provided to secure the locating plates on rod 11 in a position to suit the width of the cards which are to be counted.

Angle plates 13 are attached to the locating plates 10 and 10' by screws or any other suitable or convenient means, these plates being utilized to limit the forward movement of the cards. I mount the rod 11 adjacent the ends of the side panels 6 and 6', also upon rod 11, which has its ends mounted in the panels 6 and 6' which is provided with a block 14. This block 14 is provided with a vertical dovetail slot 15 to receive a caliper plate 16. This caliper plate 16 is slidably mounted in said slot and provision is made for raising and lowering it by means of an adjusting screw 17 which is threaded into block 14. The screw 17 is provided with a head 18 which is fitted into a horizontal slot 19 formed in the caliper 16. This provides for a minute adjustment of the caliper 16.

30 The front edge of the cards rests upon the periphery of two rolls 20 and 21 which are designed to support the ends of the cards. In practice I have found it desirable to corrugate the periphery of these right and left rolls 20 and 21. The cards are fed by a feed roll 22 which is approximately the same diameter as the right and left rolls 20 and 21. In practice I have found that this roll should be substantially 1 1/4 inches wide. It is located centrally between the support rolls 20 and 21. The feed roll 22 may be provided with a cover of medium soft tough rubber. If so constructed, this rubber should be approximately 1/4 inch in thickness or it may be found desirable to make the roll entirely of rubber. This feed roll 22 is carried by a shaft 23 which passes through a bearing formed in the side plates or panels 6 and 6'. A sprocket 24 is mounted upon the shaft 23 and with chain 24' and sprocket 24" drive the belt conveyor. The opposite end of the shaft 23 is carried in a bearing formed in the right side panel 6' and is provided with a spur gear 25 which is rigidly secured in any suitable manner by a pin or set screw.

55 The spur gear 25 is driven in a clockwise direction by a pinion 26 which is fixedly keyed on the drive shaft 27. A pulley 28 is rigidly secured to the shaft 27 by set screw 29. This pulley is rotated by means of a belt 30 driven by the electric motor 5, which is, as stated, suitably mounted upon the cross rods 3' of the frame of the machine. Adjacent to and in the rear of the main feeding roll 22 I locate a roll 32 and above it a plurality of rolls 33 which 60 hereinafter will be referred to as wringer rolls. Inasmuch as the rolls which form each pair are identical in construction, I shall only describe one set of them.

70 In practice I have found that the lower of these rolls should be made of steel and the upper one of medium hard rubber, or a similar substance, as I have found these materials are the most satisfactory for accomplishing the desired results. The roll 33 is mounted upon shaft 33' while the roll 32 is mounted upon the shaft 32'.

Means to insure a close contact between the surface of these wringer rolls 32 and 33 is provided by means of coil compression springs 35 and 35' which exert a tension upon bearings 36 and 36' in which the shafts 32' and 33' carrying the rolls 32 and 33 revolve. These bearings, which are preferably made from bronze or other suitable bearing metal, are provided with slots to slide in a guide cut in the side plates 6 and 6'. Metal plungers 37 and 37' are inserted in the coil compression springs 35 and 35'. These plungers provide an enlarged surface at the top for contact with the adjusting screws 38 and 38' which are threaded into blocks 39 and 39' which span the gap cut in the side plates 6 and 6' to permit the insertion of the bearings 36 and 36'. These blocks may be secured in place in any suitable or convenient manner. As shown, they are held by means of screws 40 and 40'. The shaft 32' which carries the lower wringer roll 32 has a spur pinion 41 mounted on its extreme right hand end. This pinion is rotated by an idler gear 42 which revolves on a stud 43 fastened to the right side panel 6' by means of a nut in the conventional manner which is so well understood so as not to require specific description. The idler gear in turn is driven by gear 25. In front of the wringer rolls 32 and 33 I mount a cross bar 44 to which is secured a cord or sheet actuated mechanism which may be in the form of a counting device 45 of standard construction. This counting device is a commercial product which is familiar to those skilled in the art and for that reason I shall not describe its construction.

I remove the metal finger which is usually provided on these counting devices and which is generally attached to the lower shaft of the counter and in its place I mount a three legged paddle wheel 46 the legs of which terminate in feet which are shaped as shown in the drawings. The feet are adapted to contact the edge of the card as it passes through the machine. At the rear of the counting device 45 I mount a second set of pairs of wringer rolls 47 and 48. 40 I have found it desirable to construct the lower roll 47 of medium soft rubber as that has been found most satisfactory in practice. It may be provided with a steel core 47', the ends of which are fitted into bearings in the side panels 6 and 6'. On the right hand end of the core 47' I mount a spur pinion 49, the teeth of which mesh with the gear 42 and is rotated thereby. The upper wringer rolls 48 of this set, as shown, there are four of them, are preferably made of steel, Figs. 10 and 11. These rolls 48 which are preferably mounted on roller or ball bearings, are carried by studs 50. The anti-friction bearings are necessary due to the high speed at which they rotate. In Fig. 11 I have shown one of the wringer rolls 48 in section to show the stud 50 upon which it revolves. As the construction of each of these wringer rolls is identical, I shall only describe one of them. The stud 50 on which the upper wringer rolls 48 of this set revolve are threaded or suitably pressed into a swinging arm 51. Means for regulating the friction between these rolls 47 and 48 is provided by flat springs 52, which are preferably secured to the under side of a collar 53, by means of screws or any other suitable manner, the collar 53 is secured to bushing 54 by a press fit, the bushing 54 being locked to the shaft 44 by set screw 54' after the desired ten- 55 60 65 70 75 80 85 90 95

sion upon roller 48 by spring 52 has been found to be correct. Swinging arm 51 is free to rotate on bushing 54. The shaft 44 is preferably supported at its ends in the said panels 6 and 6'. It will be apparent by rotating the bushing 54 upon the shaft 44 the tension of the flat springs 52 can be regulated.

After the cards have passed through the second set of wringer rolls, provision is made for carrying them away from the mechanism by means of a conveyor belt 55, which may be made of canvas or other flexible material with a rough surface. This belt 55 is preferably driven by a pair of wooden rolls 55'. The conveyor belt is supported by a rigid metal table 56, each side of the table is bent downwardly at a right angle and is attached by means of screws 56' to a metal pan 51 which houses the conveyor. The rollers 55' are provided with steel shafts 58, the ends of which are carried by bearings 59 and 60. The bearings 59 are fixedly secured to a belt tightening device 61, which is clamped to the bottom of the pan 57, being secured in place by means of screws 62 which extend through longitudinal slots formed in the bottom of the pan, so as to permit adjustment of the belt 55. The bearings 60 are preferably pressed in the side panels 6 and 6' projecting inwardly $\frac{1}{4}$ of an inch inside of a hub 63, which projects from the right and left walls of the pan 57, and which are attached permanently thereto.

The end of the pan 57 rests upon a cross rod 57' secured to the frame 1. Upon the rods 5 and 5' I mount collars 64 which are slidably mounted thereon, set screws 64' being provided to hold the collars securely against sliding movement. These collars 64 are connected by a cross rod 65. Upon this rod 65 I mount a pair of swinging arms 66, which may be spaced apart approximately 2 inches by any suitable or desired means (not shown). The arms 66 are preferably retained in position by means of collars 65'. An axle 67 is mounted in the arms 66. Upon this axle I mount a wooden roll 68, which rotates upon the axle being rotated by friction of the conveyor belt 55. Deflector horns 69 which are approximately $\frac{1}{16}$ of an inch in thickness are rigidly attached to the arms 66, in any suitable or convenient manner, so that when the cards 50 strike these horns they are guided downwardly and underneath the wooden roll 68, and intermediate it and the conveyor belt 55.

At the outer end of the pan 57, I locate an inclined plate 71 which is attached by means of the hinge 70 to the pan 51, thus providing means for covering this portion of the conveyor when the machine is not in use.

When the cards are conveyed to the rear they contact the inclined plate 71, the surface of which is smooth, permitting them to slide upward until they have assumed approximately an upright position, when due to the resistance of the cards stacked against the plate 71, the rough surface of the conveyor belt 55 will slip beneath the lower edges of the cards, and this will cause additional cards to assume an upright position before the space between the plate 71 and the roll 68 is filled.

In the front of the machine I mount a platform 72, which may be secured to the side panels 6 and 6' by means of brackets 72' which may be welded or riveted to the under side thereof, or they may be held in position by means of screws 72''. The rear edge of the platform 72 should be located at a point at approximately $\frac{1}{2}$ of an

inch in front of the wringer rolls 32 and 33. Just above this point, I mount a hold-down plate 73 the rear edge of which is located at a point approximately $\frac{1}{2}$ of an inch in front of the wringer rolls 41 and 48. This plate is slotted to provide 5 fingers 73' which extend between the rolls 33, the hold-down plate 73 is attached to the platform by means of set screws 73'' and is spaced from the platform by blocks 73'''. These blocks should be approximately $\frac{1}{2}$ of an inch wide and 10 abut the inside of the panels 6 and 6' respectively. The auxiliary platform 74 is located between the front and rear sets of wringer rolls, the ends of this platform are bent at right angles and are secured to the right and left panels 6 15 and 6' in any suitable or convenient manner.

In practice I have found it desirable to construct this auxiliary platform 74 of triangular shape, in cross section, for stiffness. A slot is provided in this auxiliary platform to provide 20 clearance for the feet of the paddle wheel 46 to enter as it is rotated by the cards.

When the cards which are to be counted are selected, one of them is placed between the periphery of the feed roll 22 and the lower edge 25 of the caliper 16 and the same is adjusted by means of adjusting screw 17 until the space between the two is just sufficient to permit a single card to pass therebetween.

30

The operation

The stack of cards of approximately 500 in number are placed on a flat surface and "jogged" until their edges are even. The cards are "jogged" preferably when held at an angle to 35 their face, thus providing a beveled arrangement for loading onto the inclined surface of the card support 8. The locating plates 10 are then adjusted on the cross rod 11 to suit the width of the cards which are to be counted. When this 40 adjustment is made, the locating plates are retained in their position by means of set screws 12.

The machine is now ready to begin the counting operation. The motor is started and through 45 the medium of the belt, pulleys and train of gears, the various rotating parts are revolved. The frictional contact against the rubber surface of the feed roll 22, on the bottom card of the stack of cards 9, will cause the bottom card to 50 be fed rearwardly. This friction is materially increased by means of gravity due to the weight of the cards on the stack and is supplemented by the weight 8'. The auxiliary rolls 20 and 21 which are provided with corrugated surface, keep 55 the cards balanced, the roughened surface of these rolls supplement the feeding action of the main feed roll 22.

As the cards are fed from the bottom at a rate which is as high as 50,000 an hour for small 50 cards, the separation of one card from another is only slightly more than the thickness of the cards, due to the fact that the one next to the bottom card is given motion just as soon as it is exposed by the movement of the bottom card. 65 As the card passes to the rear of the machine, it travels between and below the hold-down plate 73 and the platform 72 until it enters the wringer rolls 32 and 33.

The natural tendency of the card as it passes 70 through the wringer rolls 32 and 33 is to assume a horizontal position. I prevent this by the downward inclination of the hold-down plate 73, which positions the edge of the card so that it will abut the curve in the foot 46' of the saddle 75

which acts as a bearing on which the card rolls.

As the card is fed through the wringer rolls 32 and 33, it is held in position by the auxiliary platform 74 which acts as a horizontal support for the card.

wheel 46. This inclination also prevents the cards from riding upwards and just over the heel of said foot.

As the paddle wheel rotates, the foot 46' passes through the slot 74' in the auxiliary platform 74, this movement of the counting mechanism being clearly illustrated in Figs. 12 to 14 inclusive of the drawings. As shown in Fig. 12, the card 9 is just contacting the foot 46', the continued movement of the card swings the foot 46' down through an aperture 74' in the auxiliary platform until in the position shown in Fig. 13 when the counting mechanism has been operated. When in this position, the horizontal point of the cam 15 in the counting mechanism (not shown) will have passed from under the spring which will cause the paddle wheel to assume the position shown in Fig. 14, so that the card will continue its motion without resistance until the edge of the next 20 card appears when it will impinge upon the next foot of the paddle wheel.

The card now passes between the second set of wringer rolls 47 and 48 which are preferably located about $\frac{1}{4}$ of an inch below the first set, 25 these rolls again cause it to assume a horizontal position as soon as it is released from the first set of wringer rolls. As the paddle wheel 46 is forced partly by the card 9 and partly by the spring action to make $\frac{1}{3}$ of a turn, the counting mechanism 45 registers one count and the following foot rests momentarily upon the counted card, which rests upon the platform 74. This insures that the next card which is following at a high rate of speed will be well above the 30 counted card, and there will be no interference due to one card striking another, and they will therefore not get out of sequence.

The wringer rolls 47 and 48 are revolved at a higher rate of speed than the wringer rolls 32 40 and 33. This speed should be sufficient to advance the cards 9 approximately $\frac{1}{4}$ of an inch, this being permitted by the slippage between the upper wringer roll 33 and the lower one 32, thus insuring clearance between the counted card and the card following. This permits the foot 46' to complete its $\frac{1}{3}$ turn and enter the aperture 74' in the platform 74 before it is contacted by the edge of the following card.

After the card passes between the wringer rolls 47 and 48, the counted card drops approximately 50 $1\frac{1}{2}$ inches upon the conveyor belt 55, which carries it towards the rear of the machine. The surface speed of the conveyor belt 55 is approximately 7% of that the surface speed of the card being counted.

The preliminary stacking roll 68 acts as a buffer for ejected cards, causing them to pile up as shown at 68' until the bottom card will pass under it and be conveyed to the rear. The cards are ejected from the wringer rolls 47 and 48 with a varying degree of velocity, some striking the deflector horns 69 which are provided to guide them downward under the roll 68, while others will drop upon cards previously deposited upon the conveyor 55. The roll 68 may be readily adjusted for its most effective position, according to the size of the cards which are being counted, by means of sliding the collars 64 upon the rods 5 and 5'. The conveyor belt as previously described, carries the cards to the rear where they contact the inclined plate 71 which operates to stack them in approximately an upright position, from which they may be removed by the operator from time to time.

75 Although I have described with some degree of

particularity, the specific details of my invention, it should be understood that such description and drawings are merely for the purpose of showing a preferred concrete embodiment of my invention. It will be apparent to those skilled in the art, that many changes may be made in the details without departing from the spirit of my invention, and I do not wish to be understood as limiting myself to such showing and description except as such limitations may appear in the 10 hereinafter appended claims.

Having described my invention, what I regard as new and desire to secure by Letters Patent is:

1. A sheet handling machine having mechanism adapted to feed sheets to a sheet stacking mechanism, two sets of spaced pairs of wringer rolls, a sheet actuated mechanism mounted between said sets of wringer rolls, and a plurality of platforms to guide the sheet after it leaves the sheet feeding mechanism, comprising: a paddle 15 wheel on said sheet actuated mechanism, and feet on the legs of said paddle wheel, there being an aperture in one of said platforms through which said feet pass when impinged by the sheet in passing through the machine.

25

2. A sheet handling machine having mechanism adapted to feed sheets to a sheet stacking mechanism, two sets of spaced pairs of wringer rolls, said sheet actuated mechanism mounted between said sets of wringer rolls, and a plurality 30 of platforms to guide the sheet after it leaves the sheet feeding mechanism, comprising: a paddle wheel on said mechanism, and concave feet on the legs of said paddle wheel adapted to be impinged by the edge of the sheet as it is fed by 35 the second set of wringer rolls, there being an aperture in one of said platforms through which said feet pass when impinged by the sheet in passing through the machine.

30

3. A sheet handling machine having mechanism adapted to feed sheets to a sheet stacking mechanism, two sets of spaced pairs of wringer rolls, a sheet actuated mechanism mounted between said sets of wringer rolls, and a plurality of platforms to guide the sheet after it leaves the 40 sheet feeding mechanism, comprising: a paddle wheel on said sheet actuated mechanism adapted to be impinged by the edge of the sheet as it is fed by the second set of wringer rolls, and means 50 on said paddle wheel legs to prevent said sheets riding over the said legs, there being an aperture in one of said platforms through which said feet pass when impinged by the sheet in passing through the machine.

40

4. A sheet handling machine having mechanism adapted to feed sheets to a stacking mechanism, a sheet actuated mechanism, a support for a plurality of sheets, and a belt conveyor to convey said sheet from the sheet actuated mechanism towards the stacking mechanism comprising: a set of wringer rolls to carry a sheet from 55 said support and cause its edge to energize said sheet actuated mechanism, and means on said sheet actuated mechanism to make certain that the edge of the sheet will impinge the sheet 60 actuating mechanism correctly, a second set of wringer rolls to remove said sheet from the sheet actuated mechanism.

55

5. A sheet handling machine having mechanism adapted to feed sheets to a sheet stacking 70 mechanism and a sheet actuated mechanism, two sets of spaced pairs of wringer rolls, said sheet actuated mechanism being mounted between said sets of wringer rolls, and a plurality of platforms to guide the sheet after it leaves the sheet feeding 75

mechanism, comprising: a paddle wheel on said sheet actuated mechanism adapted to be impinged by the edge of the sheet as it is fed by the second set of wringer rolls, and means on said 5 paddle wheel legs to prevent said sheets riding over the said legs.

6. A sheet handling machine having mechanism adapted to feed sheets to a sheet stacking mechanism, two sets of spaced pairs of wringer 10 rolls, a sheet actuated mechanism mounted between said sets of wringer rolls, and a plurality of platforms to guide the sheet after it leaves the sheet feeding mechanism, comprising: a paddle wheel on said sheet actuated mechanism, and 15 feet on the legs of said paddle wheel.

7. A sheet handling machine having mechanism adapted to feed sheets to a sheet stacking mechanism and a sheet actuated mechanism, two sets of spaced pairs of wringer rolls, said sheet actuated mechanism being mounted between said 20 sets of wringer rolls, and a plurality of platforms

to guide the sheet after it leaves the sheet feeding mechanism, comprising: a paddle wheel on said mechanism, and concave feet on the legs of said paddle wheel adapted to be impinged by the edge of the sheet as it is fed by the second set 5 of wringer rolls.

8. A sheet handling machine having mechanism adapted to feed sheets to a sheet stacking mechanism, two sets of spaced pairs of wringer 10 rolls, a sheet actuated mechanism mounted between said sets of wringer rolls, and a plurality of platforms to guide the sheet after it leaves the sheet feeding mechanism, comprising: a paddle wheel on said sheet actuated mechanism, and feet on the legs of said paddle wheel, means for directing a portion of each sheet into contact with said feet, there being an aperture in one of said platforms through which said feet pass after being impinged by the sheet in passing through the 15 machine.

NELSON S. WELK.
